MEASURING INSTRUMENT CASE

Norman Porter, 159 Lawn Ave., Sellersville, Pa.

Filed Jan. 7, 1960, Ser. No. 58,954

Term of patent 14 years

(Cl. D52—6)

FIG. 1 is a front perspective view of a measuring instrument case, showing my new design; and

FIG. 2 is a rear perspective view thereof on a reduced scale.

I claim:

The ornamental design for a measuring instrument case, substantially as shown.
